MACHINE FOR APPLYING CANVAS TO
INNER SOLES

John A. Scott, St. Louis, Mo.

Application May 8, 1933, Serial No. 669,854

16 Claims. (Cl. 12—20)

This invention relates to machines for applying reinforcing strips of canvas to inner soles and is an improvement upon the machine disclosed in my United States Patent No. 1,926,734, dated September 12, 1933.

One of the objects of the present invention is the provision of a machine wherein the inner sole is applied to a strip of canvas disposed horizontally on a table, the inner sole being placed 10 on said canvas with its channel face placed against said canvas and applied thereto by a suitable adhesive, the inner end of said channel being arranged in juxtaposed relationship with the end of the canvas strip and the toe portion of said inner sole being utilized to move the latter and 15 canvas past a predetermined point at which the attached canvas portion is severed from the canvas strip, whereby the length of the severed portion is controlled and determined by the length 20 of the channel portion of the inner sole.

Another object of the invention is the provision of a machine wherein the canvas strip is laid flat on a table with one end abutting an upwardly presented knife edge which also forms a stop 25 against which the inner end of the channeled portion of the inner sole is placed when the latter is laid on said canvas. The machine is then actuated to lower said knife edge and to engage 30 the toe portion of said inner sole and move it and the canvas portion applied thereto past said knife edge whereupon the latter is moved upwardly and severs the canvas portion applied to the inner sole from the strip.

Still another object of the invention is to provide 35 means for engaging the canvas adjacent to said knife edge and hold said canvas stationary during the severing operation.

Further objects of the invention are to provide 40 a table, means for feeding a strip of canvas thereover, means for cutting said canvas into sections of predetermined length and including a knife mounted adjacent to one end of said table for vertical movement, and an opposed knife movable 45 in a horizontal plane into opposed relationship with the knife, said horizontally movable knife being adapted to engage the toe end of an inner sole applied by suitable adhesive to said canvas strip, and move said inner sole and said canvas strip past said cutting point.

Still further objects of the invention are to provide 50 a machine of the class described comprising a table on which the free end of a canvas strip is supported whereby an inner sole can be applied thereto by means of a suitable adhesive 55 with the channel portion presented against said

canvas strip, means for guiding the location of the inner sole on said table whereby the inner end of the channel portion thereof is arranged in vertical plane with the free end of said canvas strip, and means for moving said inner sole and said canvas strip a distance equivalent to the length of said channel portion and severing said canvas strip adjacent to the toe portion of said inner sole.

Additional objects of the invention are to provide 10 a machine which is adapted to receive an inner sole, to the channeled face of which an adhesive has been applied, said inner sole being adapted to be placed against a canvas strip supported on a table of said machine, whereby said 15 canvas strip is secured to said inner sole by means of said adhesive, and means for engaging one end of said inner sole and moving the latter and the canvas strip applied thereto past a predetermined point, whereat the attached canvas section 20 is severed from the balance of the canvas strip.

With these and other objects in view, my invention consists in certain novel features of construction and arrangement of parts, hereinafter 25 more fully described and illustrated in the accompanying drawings, in which—

Figure 1 is a side elevational view of my improved machine.

Figure 2 is a top plan view of same.

Figure 3 is an enlarged cross section taken on line 3—3 of Figure 2.

Figure 4 is a vertical cross section taken on line 4—4 of Figure 2.

Figure 5 is an end elevational view of the 35 machine.

Figure 6 is an enlarged horizontal cross section taken on line 6—6 of Figure 5.

Figure 7 is an enlarged detail cross section 40 taken on line 7—7 of Figure 2.

Figure 8 is an enlarged cross section taken on line 8—8 of Figure 2.

Figure 9 is a top plan view of same with parts 45 of the frame removed.

Figure 10 is a vertical cross section taken on line 10—10 of Figure 9.

Figure 11 is an enlarged sectional detail view 50 of one of the knives.

Figure 12 is an enlarged detail view, partly 50 broken away, of the clutch mechanism and parts associated therewith.

Figure 13 is a horizontal cross section taken through said clutch mechanism.

Figure 14 is an enlarged fragmental detail view 55

of the clutch mechanism showing the parts in disengaged position.

Figure 15 is a similar view showing the clutch members in interengaged position.

5 Figure 16 is an enlarged detail view showing the carriage actuating means.

Figure 17 is a side elevational view of same, partly in cross section.

10 Figure 18 is a bottom plan view of a sole showing the canvas strip in dotted lines.

Figure 19 is a side elevational view of the inner sole with the canvas strip attached to the channel face thereof.

15 Figure 20 is a reduced top plan view of the machine showing the location of the rack and the spraying hood.

20 Referring by numerals to the accompanying drawings, 10 indicates a support comprising a pair of side frames 11 connected together by a plurality of transverse members 12. Each frame 11 is formed at its upper end with an outwardly presented horizontal flange 14 and an inwardly disposed horizontal flange 15. The inwardly disposed flanges 15 are disposed on a horizontal 25 plane below the plane of flanges 14 and resting on the latter and projecting inwardly therefrom is a pair of side pieces 16.

Thus a horizontally disposed track or groove 30 17 is formed in the inner end of each frame 11. Engaging said grooves are the horizontally and outwardly projecting flanges 18 of a carriage 19 which is thus slidably supported between said side frames 11 and is movable in a horizontal plane longitudinally of the machine.

35 A table 20 is mounted on support 10 by means of transverse cross members 21 above said carriage 19. This table terminates short of the forward end of support 10 as indicated at 20a.

40 A horizontally and transversely disposed rod 22 is arranged between side frames 11 a suitable distance below and forwardly of the end 20a and fixed to said rod is a guide 24 which is substantially of the same width as said table. This guide is disposed obliquely and is curved at its ends and 45 serves to guide a strip of canvas A on to said table. This canvas is arranged in suitable rolls B and is supported by means of a rod 25 between a pair of brackets 26 which are fixed to side frames 11 and extend forwardly, as shown in Figure 1.

50 Each canvas strip A extends from roll B upwardly over guide 24 and then horizontally over table 20 and the outer end of said strip terminates flush with the end 20b of table 20.

55 As shown in the drawings, the machine is made to receive two rolls B of canvas so that two inner soles can be operated upon at one time. Each inner sole D is provided with a channel E which is spaced from the heel portion F as indicated at G. The inner sole is laid on each canvas strip 60 with the channel E presented downwardly against said canvas and is attached thereto by a suitable cement. Preferably this cement is applied to the inner sole immediately before the latter is placed on the canvas. However, if desired, the cement could be applied to the upwardly presented face 65 of the canvas strip.

70 As it is required to reinforce only the channel portion of the inner sole, the latter is placed in position on the canvas strip with the channel ends G abutting knife 27 and with its heel portion F extending thereover. Thus said knife is used as a guide in positioning the inner soles on the canvas and the end of the canvas strip and the ends G of the channel E always coincide.

75 The knife 27 is arranged horizontally and

transversely adjacent to the end 20b of table 20. Said knife is fixed to a vertically disposed plate 28 which is mounted for slideable movement in vertical plane in the ends of frame 11 by means of guides 29. Knife 27 is secured to said plate 28 by screws 30. This knife is movable upwardly to cut a canvas portion when the latter is moved past said knife.

80 A bar 31 is fixed to the inner side of knife 27, preferably by screws 30, a suitable distance below the cutting edge of said knife. A plurality of upwardly projecting pins 32 is fixed to the upper side of bar 31 in spaced-apart relationship. End 20b of table 20 is provided with a plurality of spaced-apart semi-circular notches which are arranged 15 concentrically with said pins and provide clearance through which said pins move upwardly with said knife 27 and engage the outer end of said canvas and hold it against displacement.

20 The plate 28 is actuated through the medium of connecting links 34 which are pivotally connected at their upper ends to the lower end of said plate, as indicated at 35, and at their lower ends to the outer ends of rock arms 36, as indicated at 37. Preferably each link 34 is adjustable 25 to regulate the distance between the points of pivotal connection thereof. Arms 36 are fixed on a rock shaft 38 which is journaled in bearings 39 formed in side frames 11. This shaft is actuated in a manner hereinafter more fully described.

30 The carriage 19 is disposed below table 20 and moves longitudinally thereof from its normal position shown in Figure 2 toward the table end 20b and the vertically movable knife 27. An extension 40 projects upwardly from the carriage 35 between each side piece 16 and the corresponding side edge of the table. A horizontally and transversely disposed bar 41 is fixed at its ends to said extensions 40 by screws 42. This bar is spaced a suitable distance above table 20 and carries a pair of knives 44 which are pivotally mounted thereon, as indicated at 45, and have their cutting edges spaced from said table. Each knife is engaged by a yielding spring 46 which yieldably holds the knife in an outwardly and oblique position which permits said knife to move against said bar 41 and assume upright position when pressure is applied to the outer surface of said knife as when it engages the toe edge of the sole when the latter is placed on the table. The cutting edge 40 of knife 44 is arranged in the same vertical plane with the outer face thereof and a comb 47 is fixed in the oblique edge of the knife in spaced relation with said cutting edge. This comb is provided with a plurality of teeth or prongs 48 which 45 are presented downwardly.

50 When the knife 44 occupies normal or oblique position (see Fig. 10) said prongs 48 are disposed above the canvas in spaced relation therewith. When, however, knife 44 is moved toward bar 41, 60 as when said knife strikes the toe portion of a sole placed on the table, said prongs engage said canvas and pull it over the table simultaneously with the movement of the carriage while the inner sole and that portion of the canvas located between the carriage and knife 27 is also moved by virtue of the engagement of knife 44 with the toe portion of said inner sole. Just before the inner sole and the canvas strip are moved by the carriage, knife 27 and pins 32 are lowered below the 65 horizontal plane of the table in order not to impede the progress of said canvas strip and said inner sole past the vertical plane of movement of said knife 27.

70 When carriage 19 reaches its outermost position

tion with its knife 44 arranged in cooperative relation with knife 27, the latter is actuated to move upwardly and sever that portion of the canvas which is attached to the inner sole, the line of severance being disposed in vertical plane with the toe portion of the latter.

A horizontally disposed shelf 49 is arranged adjacent to the ends of support 10 and is preferably attached to guides 29 and serves to receive the inner soles with the canvas strips attached thereto.

Upon the upward movement of knife 27 pins 32 move upwardly to engage the severed end of the canvas strip and hold the latter taut while the carriage and knife 44 move to normal position. A bar 50 is disposed transversely between side pieces 16 adjacent to carriage 19 when the latter occupies normal position and rearwardly thereof and this bar is pivotally mounted in said side pieces and extends obliquely in the direction of movement of the canvas. The lower edge of said bar has fixed thereon a plurality of pins or prongs 51 which rest on said canvas and permit movement thereof in one direction only and hold it against retractive movement.

The carriage 19 is actuated by an oscillatory arm 52 which is loosely mounted at its lower end on a shaft 54. This arm terminates a suitable distance below the carriage and receives the bifurcated lower end 55 of a forked member 56. The upper spaced ends 57 thereof are pivotally mounted on a horizontally and transversely disposed rod 58. A pair of arms 59 have their outer ends 60 connected to said rod 58 adjacent to the respective ends 57 while the inner ends of said arms are pivotally mounted on a rod 61 disposed parallel with rod 58. This rod 61 has its ends fixed in the sides 19a of carriage 19 and is disposed above the web portion 19b which connects said sides and flanges 18 of said carriage.

Arm 52 is formed with a longitudinally disposed channel 52a which is presented to one side of said member and operating in said channel is a roller 62 loosely mounted on one side of a vertically disposed cam disk 63. The latter is revolvably mounted on a stud shaft 64 by means of a tubular sleeve 65 formed integral with said disk. Stud shaft 64 has a reduced portion 64a which is stationarily held in bearing 66 formed in one of the side frames 11.

Cam disk 63 is disposed between arm 52 and bearing 66 and as said disk is actuated roller 62 revolves around the axis thereof and imparts oscillating motion to arm 52 which in turn causes reciprocating movement of carriage 19.

Upon the completion of its movement the carriage occupies position shown in Figures 1 and 2 while at the end of the forward movement carriage 19 is located adjacent to end 20b of table 20 and knife 44 of said carriage bears against knife 27. The ends of knife 27 are formed with upward extensions 27a which are adapted to be engaged by knife 44, thereby causing the latter to assume vertical position prior to the cutting operation and also insuring efficient and proper contact between the knives. Preferably member 56 has a slight yielding movement relatively to arm 52. The ends 55 of member 56 are pivotally mounted on the upper end of arm 52 by means of a horizontally disposed pin 67. Another pin 68 is fixed in bar 52 below pin 67 and its ends project outwardly through openings 68a formed in the ends 55. These openings are sufficiently large to allow a definite movement or play of member 56 relatively to said arm. A coiled spring

69 is interposed between the extremity 52a of arm 52 and member 56 and an adjusting screw 69a is screw-seated in said member 56 and has its inner end engaging said extremity 52a. By means of this adjusting screw 69a the carriage 19 and parts associated therewith can be properly adjusted with respect to knife 27.

The means for actuating knife 27 are set in operation by the cam disk 63. The latter is provided on one side with a cam race 63a in which operates a roller 70 carried by the upper end of a rock arm 71. This rock arm is fixed to shaft 38 and extends upwardly therefrom. The cam track or race is shaped to rock arm 71 and shaft 38 and cause the upward movement of arms 36 and knife 27 in accordance with the movement of the carriage 19. Thus when the forward movement of carriage 19 is commenced, knife 47 is brought downwardly so as to place the upper edge thereof below the horizontal plane of table 20 and permit free movement of the canvas placed thereon. Just at the completion of the forward movement of carriage 19, knife 27 is moved upwardly to its normal position, thereby severing the canvas at this line, whereupon that portion of the canvas which is attached to the ribbed or channeled face of the inner sole is severed from the canvas strip located on table 20.

The cam disk 63 is driven by a sprocket wheel 72 which is loosely mounted by means of a tubular hub 73 on the sleeve 65 of cam disk 63. A chain 74 operates over said wheel 72 and a sprocket wheel 75 which is mounted on a shaft 16. This sprocket wheel 75 is conjoined with a large pulley 77 over which operates a belt 78 of a motor 79. The latter is mounted on a bracket 80 which is fixed to and extends downwardly from shaft 54 (see Fig. 1). Sprocket wheel 72 is constantly driven from motor 79 by the connections just described and the cam disk 63 is normally disengaged from said sprocket wheel 72 and is adapted to become operatively associated therewith upon the operation of a treadle 81.

The operating connection between disk 63 and wheel 72 is effected by a clutching mechanism 82 which consists of a clutch member or ring 83 fixed to wheel 72 and a clutch pin 84 disposed in cam disk 63. Pin 84 is horizontally disposed and loosely mounted in a bearing 85 formed in disk 63 and the outer end of said pin projects outwardly from said disk and has fixed thereto a short arm 86. This arm extends outwardly from the axis of disk 63 and operates between two spaced-apart stops 87 and 88 fixed to and extending transversely from disk 63. A coiled spring 89 has one end anchored on said disk and has its other end connected to said arm 86 and tends to hold said arm against stop 87 or in a position disposed at an angle to the radius of said disk. A bell crank 90 is loosely mounted on shaft 38 to one side of disk 63 and has its upwardly presented arm 90a disposed upwardly and terminating in the path of movement of arm 86. A coiled spring 91 is anchored at one end and has its other end connected to the end of the horizontally disposed arm 90b and tends to hold said bell crank in position to engage said arm 86. A connecting link 92 has its upper end connected to said horizontal arm 90b and has its lower end connected to an arm 93 which is fixed to a shaft 94. This shaft is loosely mounted in a bearing 94a formed in one of the side frames 11. The outer end of said shaft extends outwardly and has fixed thereto treadle 81. Thus when said treadle is depressed shaft 94 is rocked, thereby imparting through

link 92, rocking motion to bell crank 90 so that the upper end of arm 90a is moved out of engagement with the outer end of short arm 86 and the latter is permitted to move under the influence of spring 89 into engagement with stop 87. When the treadle is released, spring 91 restores the parts to normal position (shown in Figure 12) whereupon the outer end of arm 86, during its cycle of movement, is brought against said arm 90a and is caused thereby to move against stop 88, thereby disengaging the clutch members from each other and rendering disk 63 stationary.

Arm 93 is provided with an extension 93a, the end of which is screw-threaded and provided with a screw 95, which bears against the frame 11. The purpose of this screw is to provide a stop and limit the inward movement of the upper arm 90a of bell crank 90. By adjusting said screw 95, the normal or inward position of said bell crank can be regulated.

The inner end 84a of pin 84 extends inwardly toward sprocket wheel 72 and past clutch member 83. Said arm is partially cut away, as indicated at 84b, so as to provide clearance between it and the inner face 83a of ring 83. This ring is provided with a plurality of spaced semi-circular notches 83b which are substantially of the same radius as the radius of pin 84. When the treadle is not actuated, the parts occupy position shown in Figure 12 and the pin occupies position shown in Figure 14. In this position the pin, by virtue of its cut-away portion 84b, clears ring 83 as indicated by line X—X in said figure. Thus the sprocket wheel 72 is free to operate without affecting cam disk 63. When the treadle is depressed, bell crank 90 is moved out of engagement with arm 86 so that the latter can move downwardly against stop 87 by virtue of spring 89. This movement of arm 86 causes partial rotation of pin 84, as indicated by line Y—Y in Figure 15, whereupon said pin is moved into the path of one of the circular notches 83b of ring 83 and the parts become interengaged, thereby actuating disk 63. If the treadle is now released, disk 63 continues to move to complete the cycle of its movement and just before the completion of its movement, arm 86 strikes the upper end of arm 90a of bell crank 90 and is moved thereby against stop 88, thereby bringing pin 84 into the normal position shown in Figure 14, whereupon sprocket wheel 72 is disengaged from disk 63 and the latter and parts associated therewith are rendered stationary.

The arm 52 which is freely mounted on shaft 54 is held against longitudinal movement by collars 96 fixed on said shaft adjacent to each end of said arm.

Where the soles are sprayed with rubber cement, preferably a rack 97 is arranged to one side of the machine to hold a supply of inner soles. A hood 98 is disposed to one side of said rack and a spray gun, such as 99, is arranged in said hood (see Fig. 20). The operator stands on the treadle side of the machine and with his left hand takes an inner sole from rack 97 and holds it in the hood so that the channeled face thereof is sprayed from the gun 99 which may be held or controlled by the right hand of the operator. When the inner sole is sprayed it is laid on the strip of canvas disposed on table 20 with the channel or sprayed side against the canvas and with the channeled ends G abutting the knife 27 so that the heel portion F extends over said knife, as shown in dotted lines in Figure 2.

The operator now sets the machine in opera-

tion by depressing treadle 81. This throws in engagement sprocket wheel 73 and disk 63 whereupon oscillatory arm 52 and rocking arms 36 are operated. Arms 36 cause knife 27 and pins 32 to disappear below the horizontal plane of table 20 and arm 52 moves carriage 19 forwardly. During this forward movement of the carriage, knife 47 is brought in contact with the toe portion of inner sole D causing the latter and the canvas strip A attached thereto to move forwardly or toward shelf 49.

When the carriage 19 reaches the end of its forward movement, knife 44 is disposed in a vertical plane with knife 27 and the inner sole D is arranged wholly to one side thereof or on shelf 49. Arms 36 are now moved upwardly (by virtue of cam race 63a and arm 77), thereby causing knife 27 to move against knife 44 and sever the canvas strip on line H—H or flush with the toe portion of said inner sole so that the latter can be removed with the severed portion of the strip attached to the channel face thereof.

The carriage then moves rearwardly to its home position, whereupon the driving connection between sprocket wheel 73 and cam disk 63 is disconnected by the arm 86 striking the upper end of bell crank 90 so that the pin 84 is actuated or partially rotated to move the end 84a thereof out of engagement with the clutch ring 83.

The strip A extends over the table 20 and terminates adjacent to knife 27. The latter forms a stop or guide against which the ends G of the channel E are placed when the inner sole D is placed on the canvas strip. While the distance traveled by carriage 19 is fixed, the strip is not moved or pulled until said carriage engages the toe portion of the inner sole so that the strip is always moved over the table only the distance equivalent to the distance between the toe portion of the inner sole and the arms G of the channel E. In this manner the canvas strip is always cut accurately in accordance with the length of the channel portion and no adjustment of the machine is necessary when operating upon inner soles of different lengths. Thus inner soles of various lengths can be placed on table 20 interchangeably and the machine automatically cuts the canvas into sections of corresponding lengths.

The machine is one simple construction, does not require experienced workmen to operate it, and is quick and efficient in performing its intended functions.

I claim:

1. In a machine of the class described, the combination of a table adapted to have a strip of canvas laid thereon and an inner sole placed on said strip with the channeled face thereagainst and secured thereto by a suitable adhesive, a downwardly and transversely disposed knife mounted for movement in a horizontal plane above said table and adapted to engage the inner end of said inner sole and move it and the canvas attached thereto longitudinally of said table, and an upwardly and transversely disposed knife mounted in said table and movable upwardly into engagement with the first-mentioned knife for severing said strip flush with said inner end of said inner sole.

2. In a machine of the class described, the combination of a table adapted to have a strip of canvas laid thereon and an inner sole placed thereagainst and secured thereto by suitable adhesive, a downwardly presented transversely disposed knife movable longitudinally of said table and spaced thereabove and adapted to engage the

- inner end of said inner sole and move it and the canvas strip attached thereto longitudinally of said table, and an upwardly and transversely disposed knife mounted in said table and movable in a vertical plane into engagement with the first-mentioned table for severing said strip adjacent to the inner end of said inner sole upon the completion of the forward stroke of said first mentioned knife.
3. In a sole reinforcing machine, the combination of a table adapted to have one end of a canvas strip laid thereon and an inner sole placed against said strip with the channeled face down and secured thereto by suitable adhesive, a carriage movable above and longitudinally of said table, a downwardly presented transversely disposed knife mounted on said carriage for engaging the inner end of said inner sole on the forward stroke of said carriage, and moving said inner sole and said canvas longitudinally of said table, and an upwardly presented knife mounted for vertical movement in said table into engagement with the first-mentioned knife for severing said canvas upon the completion of the forward stroke of said carriage.
4. In a machine of the class described, the combination of a table adapted to have laid thereon a strip of canvas and an inner sole placed with the channeled face against said strip and secured thereto by suitable adhesive, a member mounted for movement in a horizontal plane and longitudinally of said table in spaced-apart relation with said canvas and said inner sole, a downwardly presented transversely disposed knife mounted on said member and adapted to engage the inner end of said inner sole and move it and the strip on said table past a given point, and an upwardly presented knife mounted for movement in vertical plane in said table and cooperating with the first-mentioned knife for cutting the strip portion attached to said sole flush with the inner end of the latter.
5. In a machine of the class described, the combination with a table adapted to have laid thereon one end of a strip of canvas and an inner sole placed with the channeled face against said strip and secured thereto by suitable adhesive, of a transversely disposed upwardly presented knife movable in a vertical plane adjacent to one end of said table, a downwardly presented transversely disposed knife movable in a horizontal plane above said table in spaced-apart relationship with said canvas and adapted to engage the inner end of said inner sole and move it and the strip attached thereto longitudinally of said table past said first-mentioned knife, and means for actuating the latter to engage the second-mentioned knife to cut said strip flush with the inner end of said inner sole.
6. In a machine of the class described, the combination with a table adapted to receive one end of a strip of canvas and an inner sole placed with the channeled face against said canvas and secured thereto by suitable adhesive, of a transversely disposed knife movable in a vertical plane in said table, a carriage movable in a horizontal plane above said table and longitudinally thereof, a member mounted in said carriage transversely of said table and adapted to engage during the forward movement of said carriage the inner end of said inner sole and move it and the strip attached thereto past said knife, and means for actuating said knife to cut said strip flush with said inner end of said inner sole.
7. In a machine of the class described, the combination with a table adapted to receive a strip of canvas and an inner sole placed with the channeled face against said canvas and secured thereto by suitable adhesive, of a transversely disposed knife movable in a vertical plane in said table and having its cutting edge presented upwardly, a carriage movable in a horizontal plane above said table and longitudinally thereof, a transversely disposed downwardly presented knife mounted on said carriage and adapted during the forward movement of said carriage to engage the inner end of said inner sole and move it and the strip attached thereto forwardly, and means for actuating said upwardly presented knife to move into engagement with the other knife and sever said strip flush with the inner end of said inner sole.
8. In a machine of the class described, the combination with a table adapted to have laid thereon a strip of canvas and an inner sole, the latter being placed with the channeled face downwardly and secured to the strip by suitable adhesive and with the toe end presented inwardly, of a carriage movable in a horizontal plane above said table and longitudinally thereof, a member mounted in said carriage transversely of said table and adapted to engage during the forward movement of said carriage the toe end of said inner sole and move the latter and the strip attached thereto longitudinally of said table, and means for severing the strip portion attached to said inner sole flush with the toe end thereof upon the completion of the forward stroke of said carriage.
9. In a machine of the class described, the combination with a table adapted to have laid thereon a strip of canvas and an inner sole, the latter being placed with the channeled face downwardly and secured to the strip by suitable adhesive and with the toe end presented inwardly, of a vertically movable knife disposed transversely of said table with the cutting edge presented upwardly and normally projecting above the plane of said table and forming an abutment for the inner end of the channel of said inner sole, a transversely disposed knife movable in a horizontal plane above said table and having its cutting edge presented downwardly and adapted to engage the toe end of said inner sole and move the latter and said strip past said upwardly presented knife, and means for actuating the latter to move below the plane of said table before the commencement of movement of said horizontally movable knife and to move upwardly into engagement with the latter to sever the canvas strip upon the completion of the forward movement thereof.
10. In a machine of the class described, the combination with a table adapted to have laid thereon a strip of canvas and an inner sole, the latter being placed with the channeled face downwardly and secured to the strip by suitable adhesive and with the toe end presented inwardly, of a vertically movable knife disposed transversely of said table with the cutting edge presented upwardly and normally projecting above the plane of said table and forming an abutment for the inner end of the channel of said inner sole, a carriage movable in a horizontal plane above said table, a transversely disposed knife mounted on said carriage and having its cutting edge presented downwardly and adapted to engage the toe end of said inner sole and move the latter and said strip past said upwardly presented knife, and means for actuating said vertically movable knife and said carriage whereby said vertically movable knife is moved below the plane of said table before the commencement of movement of

said carriage and is moved upwardly into engagement with the other knife to sever said strip upon the completion of the forward movement of said carriage.

- 5 11. In a machine of the class described, the combination of a table adapted to have placed thereon a strip of canvas and an inner sole secured to one face thereof, a carriage movable in a horizontal plane above said table and longitudinally thereof, said carriage being spaced from said table to clear said canvas and said inner sole, a transversely disposed member fixed to said carriage and spaced from said table to clear said canvas, engage one end of said inner sole and move it and said strip of canvas over said table past a given point, and means for severing that portion of canvas attached to said inner sole from the remainder of said strip.
- 10 12. In a machine of the class described, the combination of a table adapted to support a strip of canvas and an inner sole having the channeled face secured to the latter, a vertically movable knife mounted adjacent to one end of said table, a carriage movable in a horizontal plane above and longitudinally of said table and adapted to engage one end of said inner sole and move it and the canvas past said knife, and means for actuating said carriage and said knife whereby the latter is actuated to sever said canvas strip flush with that inner end of said inner sole.
- 15 13. In a machine of the class described, the combination of a table adapted to support a strip of canvas and an inner sole secured to the latter, a carriage movable in a horizontal plane above said table and adapted to engage one end of said inner sole and move it and said strip of canvas longitudinally of said table, a downwardly presented knife mounted on said carriage and yieldably held in oblique forward position and movable into upright position upon engagement with said inner sole, and an upwardly presented knife mounted adjacent to one end of said table and operable in a vertical plane into engagement with the knife of said carriage for cutting said strip transversely flush with the inner end of said inner sole.
- 20 14. In a machine of the class described, the combination of a stationary table adapted to support a strip of canvas and an inner sole, the latter being positioned on top of and having its channeled face secured to said strip, a carriage movable longitudinally of said table above said

strip and said inner sole, a transversely disposed member fixed to said carriage and spaced from said canvas strip and adapted to engage the inner end of said inner sole and move the latter and the entire canvas strip past a given point, means for severing the section of the strip attached to said inner sole, and mechanism for actuating said carriage and said means in time relation with each other.

5

15 15. In a machine of the class described, the combination of a stationary table adapted to receive a strip of canvas and an inner sole secured to the upper face thereof, a carriage mounted in said table for movement in a horizontal plane, a transversely disposed downwardly presented knife fixed to said carriage and spaced from said strip and adapted to engage one end of said inner sole and move the latter and said canvas strip past a given point, an upwardly presented transversely disposed knife mounted in said table at said given point and movable in a vertical plane to engage the first-mentioned knife and cut the section of strip adjacent to said end of said inner sole, an oscillatable lever for actuating said carriage, an actuating disk operatively associated with said lever, driving means, means for interengaging said driving means with said actuating disk, a rock shaft, a member fixed on said shaft and associated with said disk, and means operable by said rock shaft for actuating said upwardly movable knife.

20 25 30 35

40 16. In a machine of the class described, the combination with a table adapted to support a canvas strip and an inner sole attached thereto, and a carriage operable in a horizontal plane, of a transversely disposed downwardly presented knife fixed to said carriage and adapted to engage one end of said inner sole to move the latter and said strip over said table, an upwardly presented knife disposed transversely in one end of said table, an actuating disk, an oscillatable lever operable by said disk for actuating said carriage, a rock shaft operatively associated with said disk, rock arms fixed to said shaft, and connecting links between said arms and said upwardly presented knife for moving the latter upwardly into engagement with the first-mentioned knife for cutting said canvas strip flush with the end of said inner sole.
